UNITED STATES PATENT OFFICE.

THEODORE A. SPERRY AND CORNELIUS R. UMBENHOWER, OF INDIANAPOLIS, INDIANA.

CONCRETE-BLOCK MACHINE.

1,307,796.

Specification of Letters Patent. Patented June 24, 1919.

Application filed September 7, 1918. Serial No. 253,075.

To all whom it may concern:

Be it known that we, THEODORE A. SPERRY and CORNELIUS R. UMBENHOWER, citizens of the United States, and residents of the city 5 of Indianapolis, county of Marion, and State of Indiana, have invented certain new and useful Improvements in Concrete-Block Machines, of which the following is a specification.

- 10 Our invention relates to concrete block machines in general and more specifically to that class of machines employed in constructing or forming concrete blocks for building purposes such as walls, foundations, 15 silos, culverts, etc., and has for its principal object the forming of such blocks from a predetermined volume of material compressed to uniform size and configuration. A further object is to form such 20 blocks under vertical pressure applied simultaneously from above and below. A further object is to provide means for forming such blocks under such simultaneous pressure through the instrumentality of a lever, the 25 same lever being utilized to eject the block from the machine after compression. A further object is to provide a machine to compress such blocks with one motion of said lever and to eject said blocks with a subsequent 30 motion of the same lever. A further object is to provide a machine on which molds or forms of various shapes or sizes may be interchangeably employed, said molds being interchanged with a minimum 35 of labor or time. A further object is to provide a machine that can be employed to form different sizes or shapes of blocks within any given mold or form.

With these and other objects in view our 40 invention consists in its fundamental essence in the combination and arrangement of parts hereinafter described, it being understood that the invention covers such modifications as come legitimately within the scope of 45 the appended claims.

The invention will be best understood by reference to the accompanying drawings which form a portion of this specification, and in which like parts bear like numerals 50 throughout. In the drawings—

Figure 1 is a front elevation of the device, the mold and upper pressure head being shown in section on line 1—1 of Fig. 5. Fig. 2 is an end elevation of the device in normal or neutral position. Fig. 3 is an end elevation in the position of having just

ejected a block, the mold being in section. Fig. 4 is a sectional plan view on line 4—4 of Fig. 1. Fig. 5 is a top plan view of the mold and upper pressure head. Fig. 6 is a 60 fragmentary elevation of the compressing mechanism in the position of maximum and Fig. 7 is a sectional elevation of the compressing mechanism in a normal position as seen from the inside of the frame. 65

Referring more particularly to the drawings it will be seen that the machine is composed of three fundamental subdivisions consisting of the frame work which is designated in general by the numeral 8, the 70 mold or form designated by the numeral 9 and the upper compression head designated by numeral 10. The frame 8 consists essentially of the side members 11 connected by the top frame 12 and a plurality of side 75 bars 13, the side members having suitable supporting feet 14. Side members 11 are provided with suitable bearings 15 carrying a horizontal shaft 16 to the extremities of which are fixedly attached lifting levers 17 80 operated by a U-shaped handle 18 seated within the sockets 19 in levers 17. The side bars 13 are provided with a plurality of guiding lugs 20 in which a plurality of lifting rods 21 move vertically, the upper ends 85 of said rods being guided in apertures in the top plate 12. Lifting rods 21 are interconnected above the lugs 20 by a plurality of cross heads 25 having lock or adjusting nuts 23 to adjustably retain said cross heads 90 in fixed position on said rods, the rods being threaded as at 24 for such adjustment. The cross heads are interconnected by a rod 26 which may be reinforced if desired for additional stiffness by the truss rod 27 and 95 truss block 28. An additional lifting rod 29 may also be utilized if found desirable.

Mounted on the rod 26 are a plurality of lifting dogs 30 which are preferably offset as at 31 to pass through the side members 11 and which serve as connecting links between cross heads 25 and lifting levers 17. Levers 17 are provided with forwardly projecting lugs 34 carrying fixed studs 35 and with rearwardly projecting lugs 32 carrying studs 33, these lugs being further extended rearwardly as at 36 carrying studs 37 near their outer extremities. Lifting dogs 30 are provided with suitable notches or recesses 38 near their medial portion to 110 engage with studs 33 in certain positions, said recesses being provided with heels 40

for a purpose hereafter apparent. Lifting dogs 30 are also provided with notches or recesses 41 on the opposite edges near the lower extremity of said dogs, these notches 5 being provided with striking surfaces 42 and 43 for co-action with studs 37.

Upper compression head 10 is connected to and operated by levers 17 through the side bars 44 which are off-set as at 45 to provide clearance for hubs of levers 17 when in position shown in Fig. 3. Top frame 12 is provided with lugs 47 which contact laterally with bars 44 as at 46 and rearwardly with the same bars as at 48' for purposes 10 to be hereafter explained. The mold or form 9 consists essentially of a frame 48 which may be of any size, shape or configuration fixedly attached to a base member 49 and preferably spaced therefrom by 15 lugs or supports 51 and may be provided with suitable core members 50. Base 49 is provided with a plurality of downwardly projecting lugs 53 which are detachably connected to frame 12 by bolts 52. The molds 20 are provided with loosely fitting pallets 54 which are supported as at 55 on lifting rods 25 and which serve as a lower compression and ejection plate for the block or compressed member 56. A similar plate 57 is 30 detachably connected to the frame 58 of upper compression head 10, this frame being provided with projecting lugs 59 carrying horizontal shaft 60 to which is pivotally connected the upper ends of side bars 44. 35 Frame 58 may be stiffened, if so desired, by a truss rod 61, and is also provided with projecting lugs 59' which contact in certain positions with the upper face of mold 48 to limit the downward motion of said compression head 10. To lugs 59' are pivotally connected a plurality of links 62 carrying a scraper bar 63. The upper edges of mold 48 carry a plurality of strikes or stops 64 which contact with side bars 44, 45 as will be hereinafter explained.

There may also be provided a plurality of latches 65 pivotally attached to side frames 11 in proximity to lifting dogs 30 for purposes to be hereinafter made evident. 50 In operation compression head 10 is moved backward to the position shown in Fig. 3, the compressing mechanism being essentially in the position shown in Fig. 2. A pallet 54 is placed in the bottom of the mold resting on base 49. The mold is then filled with prepared concrete and the compression head 10 is manually moved forward to position shown in Fig. 2. The scraper 63 in passing over the mold sweeps off any surplus quantity of concrete, thus measuring a definite quantity within the mold. Lever 18 is then drawn forward, the lever arm 34 causing compression head 10 to move downward. This head is positioned or guided 60 in its downward travel by lugs 64 and 65

contacting with side bars 44 which causes the top pallet 57 to enter the top of the mold. The same motion of lever 18 causes stud 33 to move upwardly and through the lifting dogs 30 and cross heads 25 produces an upward motion of rods 21 and pallet 54, 70 thus compressing the concrete between pallets 54 and 57. It will be noticed that recess 38 in the dogs 30 is deeply indented as at 39, so that the upper compression head 10 moves downward a predetermined distance before the upward motion of bottom pallet 54 commences, thus insuring the top pallet 57 to be entered within the mold before bottom pallet 54 commences its upward motion and so prevents the unintentional ejection of any of the concrete from the top of the mold. 75

When the compressive action is complete, as in Fig. 6, the handle 18 is again raised 80 to a vertical position and swung backward until studs 37 engage with recesses 41, the heel 40 of recess 38 contacting with the hubs of lifting levers 17 to insure studs 37 passing over the points 42 and contacting with striking surfaces 43 so they will enter recesses 41. At the same time compression head 10 is swung backward to approximately the position shown in Fig. 3 and handle 18 is then again drawn forward and 85 the bottom pallet 54, together with the compressed block 56, is forced upwardly out of the mold by the dogs 30, cross heads 25 and lifting rods 21, as shown in Fig. 2. The block and pallet are then manually removed, a new pallet placed in position and lever 18 returned to normal position, when 90 the cycle of operations is complete. In returning to normal position after ejecting a block the off-set portions 31 of dogs 30 come 95 in contact with the ends of latches 65 which temporarily retards their downward motion and causes studs 37 to become disengaged from recesses 41, leaving these dogs in position to be again acted upon by 100 studs 33.

It will be further seen that blocks of varying thicknesses may be made within any given mold by adjusting the lock nuts 23 engaging with cross heads 25. It is found 115 preferable in practice to surround the threaded portions of rods 21 with protecting tubes where these rods slide vertically within the guides 20. It will also be seen that by suitably adjusting the lock nuts 120 23 upon the rods at either end or either side of the machine that blocks may be made that will taper either end-wise or side-wise, making blocks suitable for arches or culverts. It will also be understood that molds 125 of any size or shape may be employed, making blocks for either curved or straight work, and that these molds may be easily and quickly interchanged by simply removing the bolts 52 from the lugs 53 and frame 130

12 and lifting the mold off complete with cores in place. The top pallet is detached from frame 58 by screws (not shown) and replaced with a different pallet to suit the 5 mold employed.

Having thus described our invention, what we claim as new and desire to protect by these Letters Patent, is:

1. In a concrete block machine, the combination with a frame and mold, of a handle 10 operating a plurality of compressing levers, said levers compressing the block simultaneously from above and from below with a single motion of said handle and means for 15 ejecting said block from said mold at a subsequent similar motion of said handle.

2. In a concrete block machine, in combination with a frame and block forming mold, a plurality of combined compressing 20 and lifting levers operated from a single handle, a plurality of lifting dogs co-acting with said levers to produce first a compression of the block within the mold and then 25 an ejection of the block from the mold at a subsequent motion of said handle.

3. In a block forming machine, the combination with a supporting frame and a 30 removably attached block forming mold, of a plurality of compressing levers having block ejecting extensions, lifting dogs co-acting with said levers first to compress said blocks and then to eject said blocks, cross heads pivotally connected with said dogs, 35 lifting rods attached to said cross heads to engage pallets within said molds, guides carried by said frames for said lifting rods,

means connected with said compressing levers for actuating an upper compressing member and means for actuating said compressing levers.

40

4. In a plastic material forming machine, a supporting frame-work, a block forming mold detachably connected to said frame-work, a horizontal shaft carried by said frame-work, a plurality of compressing and 45 lifting levers fixedly attached to said shaft, a single handle operating said levers, a plurality of lifting dogs each with a plurality of stud engaging recesses, cross heads pivotally connected to said dogs, lifting rods 50 adjustably secured to said cross heads, guides in said frames for said rods, side bars pivotally connected to said compressing and lifting levers at one extremity thereof, a compression head pivotally connected to 55 the opposite end of said side bars, a pallet detachably secured to said compression head, guides secured to said frame and said mold to co-act with said side bars, a plurality of 60 studs in compressing and lifting levers and means for selectively engaging said studs to said recesses in said lifting dogs, substantially as and for the purpose described.

In testimony whereof we have signed our names to this specification in the presence 65 of two subscribing witnesses.
